UNITED STATES PATENT OFFICE.

ARTHUR V. GULLBORG, OF CHICAGO, ILLINOIS.

ANTIFRICTION INSERT FOR SPRINGS.

Application filed January 5, 1923. Serial No. 610,766.

To all whom it may concern:

Be it known that I, ARTHUR V. GULLBORG, a citizen of the United States, and a resident of the city of Chicago, in the county of Cook and State of Illinois, have invented certain new and useful Improvements in an Antifriction Insert for Springs; and I do hereby declare that the following is a full, clear, and exact description of the same, reference being had to the accompanying drawings, and to the numerals of reference marked thereon, which form a part of this specification.

This invention relates to an anti-friction insert for springs and the devices disclosed herein embrace improvements on the devices disclosed in my co-pending application for patent, Serial No. 311,548, filed July 17th, 1919.

It is an object of the present invention to provide an anti-friction insert for springs of such construction as to exclude dirt and other foreign matter from entrance between the spring leaves and contact with the anti-friction members.

It is also an important object of the present invention to provide an anti-friction insert wherein the anti-friction members are substantially surrounded by raised portions of the retaining material for said members.

A further important object of this invention consists in the provision of a substantial closure at the outer edges of a space between the retaining material of the insert and the spring leaves.

Other and further important objects of the present invention will be apparent from the disclosures in the specification and the accompanying drawings.

The invention (in a preferred form) is shown on the drawings and hereinafter more fully described.

On the drawings:

Figure 1 is a fragmentary side elevation showing a typical leaf spring with antifriction inserts embodying the present invention positioned between the leaves thereof.

Figure 2 is a plan view of one form of insert.

Figure 3 is a section on the line 3—3 of Figure 2.

Figures 4, 5, 6, 7 and 8 are plan views each illustrating an arrangement of raised portions or ridges which may be employed in the anti-friction spring insert of this invention.

As shown on the drawings:

The anti-friction inserts of this invention comprise strips of material 1 which are of substantially the same width as the spring leaves between which they are to be inserted and the ends of which are preferably formed to conform to the configuration of the ends of the spring leaves. Said strips of material 1 are preferably formed of paper, pulp or other suitable material which is adapted to wear by attrition, and has imbedded therein or otherwise suitably associated therewith a plurality of anti-friction members which are relatively hard as compared to the spring leaves and which preferably comprise hardened steel balls 2. Said balls 2 which are ordinarily of such diameter that they project from either side of the strip of material 1 in the manner indicated in Figure 3, are adapted when said strip 1 is placed between adjacent spring leaves to wear initial guideways in the strip of material 1 due to the movement imparted thereto by the relative movement of said spring leaves. Initial guideways formed in the strip of material serve to temporarily retain the anti-friction members or steel balls in a predetermined path of movement and the continued relative movement of the spring leaves soon causes the balls, which are of harder material than the spring leaves, to wear guideways or grooves therein and thus the positioning of the balls 2 between the spring leaves serves to greatly reduce the friction therebetween and to enhance the free relative movement thereof.

The present invention provides means which are effective in preventing the entrance of dirt or other foreign material between the spring leaves adjacent the strip 1. Means which are provided for this purpose comprise ridges 3 and 4 which, as shown in Figures 2 and 3, are formed by corrugating the material of said strip so that said ridges extend from the plane thereof on both sides to substantially the plane of or slightly beyond the plane of the extremities of the balls or anti-friction members 2. In the form of insert shown in Figure 2, ridges 5 and 6, similar to the ridges 3 and 4, are formed in the strip 1 inside the ridges 3 and 4.

In Figures 4 to 8 inclusive, I have illustrated various designs and arrangements of protecting ridges similar to the ridges 3 and 4, Figures 4 and 8 illustrating designs

wherein individual balls 2 are surrounded by annular ridges 7 which are connected by continuous ridges 8.

In the forms shown in Figures 5 and 6 5 substantially peripheral ridges 9, similar to the ridges 3 and 4, are supplemented by short, discontinuous ridges 10 intermediate the balls 2.

By corrugating the strip 1 to form the 10 various ridges it is possible to make the same slightly resilient so that they contact the surfaces of adjacent spring leaves, affording a line contact between said surfaces and said ridges which is effective in preventing the entrance of any dirt or foreign material therebetween. The ridges are made of the proper height relative to the diameter of the balls or anti-friction members 2 to afford such a contact with the spring leaves, and while as before stated said ridges are 15 preferably formed by corrugating the strip 1, it is apparent that the same may be formed independently of the strip 1 and affixed thereto in any suitable manner. 20 While these ridges are primarily employed for the prevention of the entrance of dirt or other foreign material between the spring leaves, it is apparent that they will also effectively act to retain a lubricant for the 25 anti-friction members in association therewith.

I am aware that details of construction and the arrangement of the ridges may be varied without departing from the spirit of 30 my invention, and I therefore do not purpose limiting the patent granted hereon otherwise than necessitated by the prior art.

I claim as my invention:

1. The combination with a leaf spring, of

strips of relatively soft material positioned 40 between the leaves thereof, relatively hard anti-friction members between said leaves associated with said strips of material, and raised resilient portions on the strips of material for preventing the entrance of foreign 45 material between the spring leaves.

2. The combination with a leaf spring, of strips of relatively soft material positioned 50 between the leaves thereof, relatively hard anti-friction members between said leaves associated with strips of material, and integral ridges on the strips of material for preventing the entrance of foreign material between the spring leaves.

3. The combination with a leaf spring, of 55 strips of relatively soft material positioned between the leaves thereof, relatively hard anti-friction members between said leaves associated with said strips of material, and ridges extending from each surface of the 60 strips of material for preventing the entrance of foreign material between the spring leaves.

4. The combination with a leaf spring, of strips of relatively soft material positioned 65 between the leaves thereof, relatively hard anti-friction members between said leaves associated with said strips of material, and means formed by corrugating said strips of material for preventing the entrance of foreign 70 material between the spring leaves.

In testimony whereof I have hereunto subscribed my name in the presence of two subscribing witnesses.

ARTHUR V. GULLBORG.
